UNITED STATES PATENT OFFICE.

FRANK MAGIDSON, OF BROWNSVILLE, PENNSYLVANIA, ASSIGNOR OF ONE-HALF TO
JACOB DAVIS, OF UNIONTOWN, PENNSYLVANIA.

SPRING-MOTOR.

1,212,788.

Specification of Letters Patent. Patented Jan. 16, 1917.

Original application filed March 22, 1916, Serial No. 85,832. Divided and this application filed July 15, 1916.
Serial No. 109,423.

To all whom it may concern:

Be it known that I, FRANK MAGIDSON, a citizen of the United States, and resident of Brownsville, in the county of Fayette and State of Pennsylvania, have invented certain new and useful Improvements in Spring-Motors, of which the following is a specification.

This is a division of my application filed March 22, 1916, Serial No. 85,832, and the primary object thereof is to provide a spring motor of improved construction which while designed primarily for coöperating with a vibrating escapement mechanism, the power of the motor may be variously utilized without regard to the means employed for controlling the unwinding of the motor spring.

In the accompanying drawings, Figure 1 is a longitudinal sectional elevation of spring motor mechanism embodying the invention. Fig. 2 is a cross section taken on line 2—2 of Fig. 1. Fig. 3 is a longitudinal section of one end of the mechanism, the section through the escapement device being taken 25 at right angles to the position thereof shown in Fig. 1. Fig. 4 is a cross-sectional elevation on line 4—4 of Fig. 1. Fig. 5 is a detail view of the washer-like element interposed between the core sections.

Referring to the drawings, the motor mechanism to which the present invention is directed is preferably arranged within an elongated casing 2 of rectangular form which may be supported in any suitable manner with reference to the mechanism to be actuated by the motor. The casing is closed at one end by head 3 in which is formed a bearing for the short shaft 4, the squared extremity 4' of the latter being adapted to 40 receive a crank for winding up the motor.

Secured to the inner end of shaft 4 is sprocket wheel 5, and projecting inwardly from this wheel is the core or spool-like support for the elongated coiled motor spring 6. This spool or core is formed in sections, 7 being the end section secured by lugs 8 and pin 8' to the inner side of wheel 5.

9 designates the inner end section of the core which is non-rotatably supported by 50 pin 10 disposed diagonally in casing 2 with its extremities confined in the casing angles as shown.

Between the opposite end sections 7 and 9

of the core are the intermediate sections 11 which are rotatable on a rod or shaft 12 extending therethrough with the opposite ends of the rod grooved at 12' and rotatably confined in core sections 7 and 9 by screws 13. Thus it will be seen that the only non-rotatable portion of the core is the innermost section 9, the opposite end section 7 and the intermediate sections 11 being rotatable relative to each other. As rod 12 is itself rotatably held, the movable spool sections may rotate either with the rod or independently thereof. By this means every possible facility is provided for preventing the motor spring 6 when wound up from deflecting laterally and so gripping and binding the core as to interfere with a uniform and regular application of spring force to the driven mechanism. Thus, even if the lateral deflection of the spring at one point tends to grip one section of the core, the remaining sections are in nowise affected and may turn freely in response to the unwinding action of the spring.

Interposed between the adjacent spool sections are the washer-like plates or heads 14 having their edges notched and with the resulting point-like projections 14' bent or deflected in opposite directions to overhang the adjacent spool sections, thereby bridging the joint between the latter and preventing convolutions of spring 6 from working therebetween which if permitted might result in clogging the mechanism and impairing the operation. Parts 14 are loosely arranged and may turn with the spool sections, or if impinged by the spring may be held against 90 turning, without retarding the operation.

The means for controlling the spring and for transmitting its power to the device to be actuated may be variously embodied. In the adaptation here shown said mechanism is so arranged as to transmit movement to a cradle, churn or other vibrating body. The controlling mechanism coöperates with ratchet wheel 5, and consists of two levers 15 and 16 arranged at opposite sides of shaft 4 and extending past opposite portions of the ratchet wheel periphery. These levers are pivoted at their inner ends at 15' and 16', respectively, to a plate 17 secured to the annular boss 3' of casing head 100 105 3. The levers are connected for unitary

movement by the bodily movable ring-like link 18 which encircles shaft 4, with arm 19 projecting from lever 15 pivoted to said link at 19', and a similar arm 20 projecting from the opposite side of lever 16 and pivotally connected at 20' to link 18. The free extremity 15'' of lever 15 extends through a slot in casing 2 and may be connected in any suitable manner, not shown, to the part or body to which vibrating movement is to be transmitted.

Pivoted to levers 15 and 16 are the oppositely disposed dogs or pawls 21 and 22 which are adapted to engage the notches of wheel 5, as in Figs. 1 and 2. A spring 23 connects dog 21 with pivot post 15' of lever 15 and a like spring 24 similarly connects dog 22 with post 16' of lever 16. With the parts thus arranged, it will be seen that movement of levers 15 and 16 in either direction from a straight line position will place the springs 23 and 24 under tension which results in moving dogs 21 and 22 either into or out of engagement with the teeth of wheel 5, depending on the direction of movement of the levers. Thus, with the levers in the position shown in Fig. 4, the movement of lever 15 toward the left has resulted in so deflecting spring 23 as to cause dog 21 to engage the ratchet as seen in Fig. 2, and at the same time the opposite deflection of spring 24 has resulted in a reverse movement of dog 22, thereby disengaging the latter from the ratchet wheel. The movements thus described result from the arrangement whereby the free portions of the spring-connected levers 15 and 16 move simultaneously in the same direction, first toward one side of the casing and then toward the opposite side.

Upon stopping the vibration of the body to which lever 15 is connected, the dog carrying levers hold the mechanism still or inoperative until the body is again started to swing, whereupon the escapement will immediately become active and will continue to operate until the body is again stopped or until the motor has become completely unwound.

50 The escapement mechanism disclosed herein is claimed in my application filed March 22, 1916; Serial No. 85,832.

I claim:

1. In a spring motor mechanism, the combination of spool-like core-forming sections arranged end to end; a shaft on which the several sections are mounted and upon which all of the sections are rotatable excepting one of the end sections, a support for the shaft and core sections to which the non-rotatable end core section is secured, a rotatable power transmitting device, and a coiled spring embracing the core sections and with means for anchoring that end of the spring which embraces the non-rotatable

core section and with the opposite end of the spring connected to the power transmitting device.

2. In a spring motor mechanism, the combination of spool-like core-forming sections arranged end to end, a shaft on which the several sections are mounted and upon which all of the sections are rotatable excepting one of the end sections, means connected to the opposite end section for transmitting power, and a coiled spring embracing the core sections and with means for anchoring that end of the spring which embraces the non-rotatable core section and with the opposite end of the spring secured to the power-transmitting end section of the core. 75

3. In a spring motor, the combination of an elongated coiled spring, power transmitting means connected to the spring, a spool-like core upon which the spring is wound 85 and consisting of a series of core sections arranged end to end, and a washer-like part interposed between the ends of adjacent sections and with projections on said interposed part extending over the core sections 90 for preventing convolutions of the spring from working between the sections.

4. In a spring motor mechanism, the combination of an elongated casing, a shaft journaled in one end thereof, a core at one 95 end secured to the said shaft and extending into the casing therefrom, a supporting arm projecting laterally from the inner end of the core and engaging opposite walls of the casing, a rotatable power transmitting device, and a spring coiled around the core and at one end connected to the power transmitting device and at its opposite end secured to said core supporting arm, said core formed in sections rotatable relatively to 100 each other whereby the power transmitting device is adapted to rotate relatively to the supported inner portion of the core.

5. In a spring motor mechanism, the combination of an elongated coiled spring, a 110 core for the spring consisting of end and intermediate sections with opposite ends of the spring secured, respectively, to the end sections of the core, a shaft extending into and rotatable within the end core sections and with the intermediate sections rotatable on said shaft, means for holding one of the end core sections from rotating, and a power transmitting device rotatable with the other end core section. 115

6. In a spring motor mechanism, the combination of a case angular in cross-section, a shaft journaled in one end of the casing, a power transmitting device secured to the shaft, a core-like support for a spring secured at one end to said shaft and extending inwardly therefrom, a transversely extending arm carried by the inner end of the support and entered in opposite angles of the casing for non-rotatably sustaining said 125 130

support end, said support formed in sections, a shaft within and connecting the intermediate sections with the end sections and with the several sections and said shaft rotatable independently of each other, and a spring coiled about the said support and held at the non-rotatable inner end of the support and with the opposite end of the spring movable with said power transmitting device.

7. The combination with an escapement mechanism, of a coiled spring for actuating said mechanism, a core on which the spring is wound, the core formed in independently

rotatable sections arranged end to end, and a washer-like part interposed between the ends of adjacent sections and with portions of said interposed part upset in reverse directions over the sections for preventing convolutions of the spring from working between the sections.

In testimony whereof I affix my signature in presence of two witnesses.

FRANK MAGIDSON.
